UNITED STATES PATENT OFFICE.

EMIL J. PETERSON, OF JACKSON, MICHIGAN, ASSIGNOR TO HAYES WHEEL COMPANY, OF JACKSON, MICHIGAN.

RIM-ROLLING MACHINE.

Application filed May 1, 1924. Serial No. 710,276.

This invention relates to improvements in rim rolling machines.

The objects of the invention are:

First, to provide an improved means for manipulating and driving the main rolls of such a machine whereby they will freely and effectively act upon an automobile rim in conforming the same.

Second, to provide an improved compensating means to permit the free movement of the forming rolls when they come into engagement with the metal of the rim.

Further objects, and objects relating to details and economies of construction and operation will definitely appear from the detailed description to follow.

I accomplish the objects of my invention by the devices and means described in the following specification. The invention is clearly defined and pointed out in the claims.

The parts of a machine necessary to understand my invention are illustrated in the accompanying drawing, forming a part of this application, in which:

Fig. I is a vertical detail sectional elevation, parts being shown in full lines, transverse to the axis of the rolls through the main parts of a rim rolling machine embodying my invention taken on the irregular line 20 corresponding to line 1—1 of Fig. II showing the gearing trains.

Fig. II is a detail sectional elevation view of the same machine, parts being shown in full lines, taken on the irregular section line 35 2—2 of Fig. I, axially and longitudinally of the rolls, the rolls being closed to final contact position.

Fig. III is a detail sectional view of the gearing trains taken on the same section line as Fig. I, showing the rolls in closed position.

Fig. IV is an enlarged detail sectional view, parts being shown in full lines, taken on the irregular line 4—4 of Figs. I, III and V.

Fig. V is an enlarged detail view, partly in section, on the irregular line 5—5 of Fig. IV, showing details of the compensating gear means.

Fig. VI is an enlarged detail sectional view through the compensating gear dog and adjacent parts showing the spring in full lines and its operative relation.

Fig. VII is a detail perspective view of the dog. 55

In the drawing similar reference characters refer to similar parts throughout the several views, and the sectional views are taken looking in the direction of the little arrows at the ends of the section lines. The parts 60 of the drawing will be considered by their numbers.

The base 1, 1 carries frame parts 2, 2 connected by a frame member 2'. The upper fixed roll shaft 3 is suitably journaled 65 in the upper part of the frame carrying the stationary forming roll 4.

The shaft 5 carries the movable roll 6 and is journaled in a suitable slide 7 carried on ways 8. The slide is actuated from the rock 70 shaft 9 having arms 10 to which are connected the links 11 which connect to the slide 7 by universal joints 12.

The rock shaft 9 is actuated by arms 13 connected by pitman 14 to cross head 15 operated from air cylinder 16 or other means which is regulated and controlled by the regulating means 17. These parts, as they do not pertain to my invention, are not illustrated or described in detail. 75 80

The machine is driven by the driving shaft 18 having driving pinion 19 meshing with the gear 20 which is keyed or otherwise secured to the fixed roll shaft 3.

The movable roll shaft 5 is driven by a 85 train of gears connecting to a gear at the central part of the main fixed shaft 3. This comprises the driving gear 21 on the said shaft, see Figs. I and II, which meshes with the intermediate gear 22 which meshes with 90 the gear 23 of the compensating gear which, by the compensating devices, drives the gear 24 which drives gear 25 which drives gear 26 which is supported in the rocker 27 which is pivoted coaxially with the gear 25. The gear 26 meshes with and drives gear 29, keyed to the shaft 5. 95

The compensating means and gear comprises the said gear 23 and the gear 24 journaled to rotate independently and provided with the compensating coupling means therebetween. The gear 23 is recessed on one face at 231 and the gear 24 is provided with a hub-like extension 241 which is provided with ratchet teeth 242 and a circumferential annular groove 243 between the 100 105

said ratchet teeth and the face of the gear 24. In a recess 232 in the face of the gear 23 is disposed a dog 233, the forward end of which, 234, is adapted to engage the ratchet teeth 242 and to swing into the recess 232 when out of engagement.

The dog 233 contains a longitudinal recess at 235 in which is disposed the actuating spring 237 having a coiled central portion 10 and projecting ends 238, 239 to hold the dog into yielding engagement with the ratchet teeth. The engaged end of the dog is rounded and fits into a rounded seat, and the opposite end is of such width as to remain in 15 engagement with the square forward end of the recess so that no pivot pin is required to keep the dog in place.

It will thus be seen that it is possible for the gear 24 to turn forward at a higher rate 20 of speed than the gear 23. The gear 24 is connected, as has been indicated, to drive the lower shaft 5 carrying the movable forming roll 6. When the rim is being formed, it is comparatively flexible and it is necessary 25 until the rolls come into quite strong engagement that both rolls be driven. If this is not done, the machine is lacking in efficiency in that the gradual spring or shaping of the metal is not insured and there will be much wastage due to rims not passing 30 inspection. Where the advance of the rolls is controlled and both rolls are driven effectively, very little wastage occurs. Great strain occurs on the machine, however, unless 35 there are compensating means and it will be seen that when the rolls contact, as indicated in Figs. II and III, that if the roll on the movable shaft is permitted to advance at a higher rate of speed than the 40 gearing and that roll is made slightly smaller than the roll on the fixed shaft, the roll on the movable shaft can be driven by the final contact and if it is allowed to roll freely, perfect rolling will be secured without 45 any undue strain. This is accomplished by the compensating means, permitting this movement to occur by allowing the gear 24 to move forward more rapidly than the gear 23. At the same time, the ratchet pawl tooth 50 242 will at once engage and drive the gear 24 when it is not being driven by the contact of the forming rolls. The engaging end of the pawl is forced into engagement by the spring 237 and the rear wall of recess 232 55 forces it forward. While the lower roll 6 is being driven from the contact with the rim it is driven at a greater rate. The teeth 242 will slide under the pawl and swing it out of engagement and it will remain out 60 of engagement so long as that action continues. This particular means is highly desirable but is not an absolute necessity in providing for the compensation which would, of course, be taken care of by a 65 simple ratchet in this position.

This particular means is very strong and effective and is very simple. It is desired to claim the same specifically as well as broadly in this special combination as pointed out in the appended claims.

I have not illustrated or described in detail the guide rolls nor the rolls for specially forming the flanges on the rim as they are merely auxiliary in their use to the main forming rolls that I have described.

I have not attempted to describe the complete machine as my invention does not pertain to the complete machine, but only to the combination and parts which I have illustrated and described.

Having thus described my invention what I claim as new and desire to secure by Letters Patent is:

1. In a rim rolling machine, the combination of a frame, an upper roll on a fixed shaft, means for driving the same, a lower movable roll on a shaft, a slide with journal bearings for said movable roll, means for advancing said slide and roll, a driving means for the fixed roll shaft, a chain of gears driven from the fixed roll shaft, one of which is supported on a rocker and connected to drive the movable roll, a compensating gear in the said chain of gears comprising independently revoluble gears with compensating pawl and ratchet drive means therebetween, the driving gear being recessed on its face and carrying a pawl and the driven gear of which has a hub-like extension with ratchet teeth disposed in said recess, a pawl recess in the face of the driving gear with a cylindrically curved convex rear portion to engage the rear end of the pawl and with a square front portion to permit the movement of the pawl therein and maintain its rear engagement, a pawl with its rear end curved to pivot in the pawl recess and with its front end squared to engage the ratchet teeth and to move freely into the said recess, the said pawl having a longitudinal slot through the rear end and in its upper face, and a spring with projecting ends and a central coil disposed in the said slot reacting between the said pawl and the bottom wall of the recess to urge said pawl into engagement, the pawl and ratchet parts being of such dimension that its outer corner remains within the square end of the recess at all times whereby the driven gear may be carried forward out of engagement with the driving gear to compensate for the varying movements of the rolls in contact with the stock when the movable roll is driven from the fixed roll more rapidly than the rate of drive of the chain of gears.

2. In a rim rolling machine, the combination of a frame, an upper roll on a fixed shaft, means for driving the same, a lower movable roll on a shaft, a slide with journal bearings for said movable roll, means for

- advancing said slide and roll, a driving means for the fixed roll shaft, a chain of gears driven from the fixed roll shaft and connected to drive the movable roll, a compensating gear in the said chain of gears comprising independently revolute gears with compensating pawl and ratchet drive means therebetween, the driving gear being recessed on its face and carrying a pawl and the driven gear of which has a hub-like extension with ratchet teeth disposed in said recess, a pawl recess in the face of the driving gear with a cylindrically curved convex rear portion to engage the rear end of the pawl and with a square front portion to permit the movement of the pawl therein and maintain its rear engagement, a pawl with its rear end curved to pivot in the pawl recess and with its front end squared to engage the ratchet teeth and to move freely into the said recess, the said pawl having a longitudinal slot through the rear end and in its upper face, and a spring with projecting ends and a central coil disposed in the said slot reacting between the said pawl and the bottom wall of the recess to urge said pawl into engagement, the pawl and ratchet parts being of such dimension that its outer corner remains within the square end of the recess at all times whereby the driven gear may be carried forward out of engagement with the driving gear to compensate for the varying movements of the rolls in contact with the stock when the movable roll is driven from the fixed roll more rapidly than the rate of drive of the chain of gears.
3. In a rim rolling machine, the combination of a frame, an upper roll on a fixed shaft, means for driving the same, a lower movable roll on a shaft, a slide with journal bearings for said movable roll, means for advancing said slide and roll, a driving means for the fixed roll shaft, a chain of gears driven from the fixed roll shaft and connected to drive the movable roll, a compensating gear in the said chain of gears comprising independently revolute gears with compensating pawl and ratchet drive means therebetween the driving gear being recessed on its face and carrying a pawl and the driven gear of which has a hub-like extension with ratchet teeth disposed in said recess, a pawl recess in the face of the driving gear with a cylindrically curved convex rear portion to engage the rear end of the pawl and with a square front portion to permit the movement of the pawl therein and maintain its rear engagement, a pawl with its rear end curved to pivot in the pawl recess and with its front end squared to engage the ratchet teeth and to move freely into the said recess, the said pawl having a longitudinal slot through the rear end and in its upper face, and a spring with projecting ends and a central coil disposed in the said slot reacting between the said pawl and the bottom wall of the recess to urge said pawl into engagement, the pawl and ratchet parts being of such dimension that its outer corner remains within the square end of the recess at all times whereby the driven gear may be carried forward out of engagement with the driving gear to compensate for the varying movements of the rolls in contact with the stock when the movable roll is driven from the fixed roll more rapidly than the rate of drive of the chain of gears.
4. In a rim rolling machine, the combination of a frame, an upper roll on a fixed shaft, means for driving the same, a lower movable roll on a shaft, a slide with journal bearings for said movable roll, means for advancing said slide and roll, a driving means for the fixed roll shaft, a chain of gears driven from the fixed roll shaft, one of which is supported on a rocker and connected to drive the movable roll, a compensating gear in the said chain of gears comprising independently revolute gears with compensating pawl and ratchet drive means therebetween to compensate when the movable roll is driven from the fixed roll more rapidly than the rate of drive of the chain of gears.
5. In a rim rolling machine, the combination of a roll on a fixed shaft, means for driving the same, a movable roll on a shaft with means for adjusting it to and from the fixed roll, a gear train for driving said movable roll, a compensating gear in said train of gears comprising independently revolute gears with compensating pawl and ratchet drive means therebetween, the driving gear of which has a hub-like extension with ratchet teeth disposed in said recess, a pawl recess in the face of the driving gear with a cylindrically curved convex rear portion to engage the rear end of the pawl and with a square front portion to permit the movement of the pawl therein and maintain its rear engagement, a pawl with its rear end curved to pivot in the pawl recess and with its front end squared to engage the ratchet teeth and to move freely into the said recess, the said pawl having a longitudinal slot through the rear end and in its upper face, and a spring with projecting ends and a central coil disposed in the said slot reacting between the said pawl and the bottom wall of the recess to urge said pawl into engagement, the pawl and ratchet parts being of such dimension that its outer corner remains within the square end of the recess at all times whereby the driven gear may be carried forward out of engagement with the driving gear to compensate for the varying movements of the rolls in contact with the stock when the movable roll is driven from the fixed roll more rapidly than the rate of drive of the chain of gears.
6. In a rim rolling machine, the combination of a roll on a fixed shaft, means for driving the same, a movable roll on a shaft with means for adjusting it to and from the fixed roll, a gear train for driving said movable roll, a compensating gear in said train of gears.

4

of gears comprising independently revoluble gears with compensating pawl and ratchet drive means therebetween, the driving gear of which has a hub-like extension with ratchet teeth disposed in said recess, a pawl recess in the face of the driving gear with a cylindrically curved convex rear portion to engage the rear end of the pawl and with a square front portion to permit the movement of the pawl therein and maintain its rear engagement, a pawl with its rear end curved to pivot in the pawl recess and with its front end squared to engage the ratchet teeth and to move freely into the said recess, the pawl and ratchet parts being of such dimension that its outer corner remains within the square end of the recess at all times whereby the driven gear may be carried forward out of engagement with the driving gear to compensate for the varying movements of the rolls in contact with the stock when the movable roll is driven from the fixed roll more rapidly than the rate of drive of the chain of gears.

In witness whereof I have hereunto set my hand.

EMIL J. PETERSON.
